UNITED STATES PATENT OFFICE.

CHARLES E. DOTY, OF NEW YORK, AND JOHN E. LATHROP, OF YONKERS, NEW YORK.

COMBINED TIE-PLATE AND ANTICREEPER.

1,199,060.

Specification of Letters Patent. Patented Sept. 26, 1916.

Application filed August 27, 1915. Serial No. 47,561.

To all whom it may concern:

Be it known that we, CHARLES E. DOTY, a citizen of the United States, and a resident of New York, county of Bronx, State 5 of New York, and JOHN E. LATHROP, a citizen of the United States, and a resident of the city of Yonkers, county of Westchester, and State of New York, have invented certain new and useful Improvements 10 in Combined Tie-Plates and Anti-creepers, of which the following is a specification.

Our invention relates to an improved tie plate and anti-creeper for use in railroad 15 construction.

One of the objects of our invention is to so construct and combine a tie-plate and anti-creeper that the anti-creeper will bite into the edge of the rail base on the side opposite the gage side of the rail.

Another object of the invention is to so construct a tie-plate and anti-creeper that the wave motion of the rail will not be interfered with, the creeper being so positioned that it may rise and fall with the rail when the load passes thereover.

Another object is to so construct the anti-creeper that it will not become loose from the rail by reason of the changes of 30 temperature.

Other objects will appear from the following specification and claims.

Referring to the drawing which forms a part of the specification; Figure 1 is a sectional view of the rail, tie-plate, tie and anti-creeper device assembled in position for work. Fig. 2 is a plan view, partly broken away, of the tie-plate and anti-creeper in assembled position, the anti-creeper being 40 shown partly in section. Fig. 3 is a perspective view of one form of anti-creeper device. Fig. 4 is a perspective view of another form of anti-creeper device. Fig. 5 is a sectional view, partly broken away, similar to Fig. 1, 45 showing a modified form of anti-creeper device in position. Fig. 6 is a sectional view on line 6—6 of Fig. 1.

In the drawing, like reference characters refer to like parts.

50 A is a cross-tie, B the tie-plate, C the rail and D the spikes shown in the usual position. A depression 10, rectangular in shape, is rolled on the face of the tie-plate next to and adjoining the shoulder 11, 55 which shoulder is adjacent to the outside

of the base 12 of the rail. The lower portion of the depression at 13 extends a short distance under the outside edge 14 of the base of the rail. A depression is also rolled, as at 15, in the shoulder 11, the total depth 60 of the depression being equal to the height of the shoulder plus the depth of the depression rolled in the face of the tie-plate. A piece of case hardened steel defined in the art as an anti-creeper 16, is so shaped that 65 it fits at its ends and bottom in the depression which has been formed in the tie-plate and shoulder. The depression measured transversely is greater than the width of the lower flange 18 of the anti-creeper so that 70 a space is provided underneath the rail for the play of the anti-creeper.

The anti-creeper is made of an integral piece of case hardened steel and is provided with upper and lower jaws or flanges 17 and 75 18 extending from the same side of the vertical integral web 19. The inner side of the vertical integral web is provided with a series of teeth 20 cut at an acute angle with the edge of the rail, the teeth extending 80 opposite to the line of direction of traffic; in other words, the line of direction of creep of the rail.

In Figs. 4 and 5, we have shown a modified form of anti-creeper in which teeth 21 85 formed at an acute angle with the horizontal are also cut in the lower face of the upper flange 17. In all forms the lower flange 18 is less in width than the upper flange and its upper face is below, as at 26, 90 the under surface of the rail, so that the rail will rest on the tie-plate and not on the anti-creeper device, as clearly shown in the drawing.

The anti-creeper device is fitted into the 95 depression which is rolled in the shoulder and face of the tie-plate with the narrower flange resting on the bottom of the depression. The rail is then placed upon the tie-plate and the edge of the base of the rail, 100 which is opposite the gage side of the rail, is inserted between the flanges of the anti-creeper device. The tie-plates with the previously inserted anti-creeper are then hammered into place so that the teeth of the 105 anti-creeper device are embedded in the rail base. The sides of the teeth which are at an acute angle extend in the line of direction of traffic. The spike holes 30 preferably $\frac{3}{4}$ " 110 square are previously formed in the tie-

plate at points on opposite sides of the rail base and the spikes D are driven in place as usual.

The anti-creeper extends, as shown, over 5 the top of the base of the rail and the upper surface of the creeper extends a short distance as at 25 above the upper surface of the shoulder in the tie-plate.

From the above description it will be seen 10 that as the action on the rail due to the passing load is on the gage side of the rail, the natural tendency is for the rail to engage tightly into the teeth of the creeper and inasmuch as the creeper is prevented from 15 moving in a horizontal direction, the rail is prevented also from having a horizontal movement, or in other words, from creeping. It will also be seen that by the use of our invention the wave motion of the rail is not 20 impeded in any way, as the creeper is free to move up and down with the rail.

Having now described our invention, what we claim as new and desire to secure by Letters Patent is:

- 25 1. In combination, a tie plate having a hole therein, a rail resting on the tie plate, the base of the rail covering a portion of the hole in the tie plate, a U shaped anti-creeper device fitting closely in the hole of the tie-plate, the upper leg only of the U shaped anti-creeper device having teeth formed in its under-surface, said teeth engaging with the upper surface of the base 30 of the rail.
- 35 2. In combination with a rail of a fixed tie plate having a hole therein, said hole being provided with substantially vertical

walls, a U shaped anti-creeper device fitting closely in said hole and embracing the edge of the base of the rail, said anti-creeper device being fitted to move bodily in a vertical direction only with the movement of the base of the rail. 40

3. In combination with a rail, a tie plate having a hole therein, a U shaped anti-creeper device fitted in the hole in the tie plate and embracing the base of the rail, a lip projecting from the top surface of the tie plate adjacent the hole therein, one face of the lip being contiguous with the outer 50 wall of the hole in the tie plate, the base of the U shaped anti-creeper device engaging the said face of the lip on the tie plate. 45

4. In combination, a tie plate having a hole therein, a rail resting on the tie plate, the base of the rail opposite to the gage side only of the rail covering a portion of the hole in the tie plate, a U shaped anti-creeper device fitting closely in the hole of the tie plate, the upper leg of the U shaped anti-creeper device having teeth formed in its under-surface, said teeth engaging only with the base of the rail opposite to the gage side 55 of the rail. 60

In witness whereof we have hereunto set our hands at the borough of Bronx, city and State of New York, this 12th day of August, 1915. 65

CHARLES E. DOTY.
JOHN E. LATHROP.

In the presence of—
JAMES A. MURRAY,
M. LOUISE YOUNG.
